HANDBAG

Theodore Rosenberg, New Rochelle, and Harry T. Silverman, Forest Hills, N. Y.

Application November 6, 1952, Serial No. 22,168

Term of patent 7 years

(Cl. D87—3)

To all whom it may concern:

Be it known that we, Theodore Rosenberg and Harry T. Silverman, citizens of the United States, residing at New Rochelle and Forest Hills, in the counties of Westchester and Queens, respectively, and State of New York, have invented a new, original, and ornamental Design for a Handbag, of which the following is a specification, reference being had to the accompanying drawing, forming part thereof.

In the drawing

Fig. 1 is a front elevational view of a handbag, showing our new design;

Fig. 2 is a side elevational view thereof;

Fig. 3 is a rear elevational view; and

Fig. 4 is an enlarged fragmentary view of a portion of the grill body.

We claim:

The ornamental design for a handbag, substantially as shown.

THEODORE ROSENBERG.
HARRY T. SILVERMAN.
